UNITED STATES PATENT OFFICE.

SIMON W. WARDWELL, JR., OF BOSTON, MASSACHUSETTS, ASSIGNOR, BY MESNE ASSIGNMENTS, TO THE UNIVERSAL WINDING COMPANY, OF PORTLAND, MAINE.

MACHINE FOR WINDING SHUTTLE-COPS.

SPECIFICATION forming part of Letters Patent No. 555,790, dated March 3, 1896.

Application filed November 8, 1892. Serial No. 451,385. (No model.) Patented in England March 25, 1893, No. 6,381; in France March 25, 1893, No. 220,702; in Belgium March 25, 1893, No. 104,051; in Germany March 25, 1893, Nos. 73,859, 74,497, 74,732, 75,022, 76,456, and 76,481; in Austria-Hungary March 25, 1893, No. 17,999 and No. 90,408, and in Italy March 25, 1893, No. 33,778/267.

To all whom it may concern:

Be it known that I, SIMON W. WARDWELL, Jr., a citizen of the United States, residing at Boston, in the county of Suffolk and State 5 of Massachusetts, have invented certain new and useful Improvements in Machines for Winding Shuttle-Cops, of which the following is a specification.

My invention, which has been patented in 10 England March 25, 1893, No. 6,381; in France March 25, 1893, No. 220,702; in Belgium March 25, 1893, No. 104,051; in Germany March 25, 1893, Nos. 73,859, 74,497, 76,456, 76,481, 75,022, and 74,732; in Austria-Hungary March 25, 15 1893, No. 17,999 and No. 90,408, and in Italy March 25, 1893, No. 33,778/267, relates to apparatus for winding cops or bails of thread, yarn, &c.; and my invention consists of certain improvements upon the apparatus set 20 forth in my Letters Patent No. 480,157, and fully set forth hereinafter and illustrated in the accompanying drawings, in which—

Figure 1 is a side elevation of my improved apparatus for winding cops or balls. Fig. 2 is an enlarged elevation of part of the apparatus sufficient to show one winding-shaft and its connections. Fig. 3 is a plan of the parts shown in Fig. 2. Fig. 4 is a transverse section of the parts shown in Fig. 2. Fig. 5 25 is a transverse section on the line 5-5, Fig. 3; Figs. 6 to 10, details of the automatic stop device.

The cop-shaft 1 is provided with an expansion-spindle *a*, so that when the cop-tube is 30 placed upon the said spindle the spindle may be expanded to hold it in place, and the thread-guide hole is in an arm 2, which is pivoted to a carrier 3, the latter being a hub upon a rock-shaft 15, which derives its motion from another rock-shaft, 4, having a forked or slotted arm 7, into the fork or slot *x* of which extends a pin 5 from the rocking carrier 3. The rock-shaft 4 is driven from a cam-wheel 13, into the 35 cam-groove of which extends a stud 12 carried by a swinging arm 10. Another stud, 9, extending from the stud 12 into a slot in an arm 8, which latter is secured to the shaft 4.

The cam thus imparts a reciprocating motion to the arm 8 and a rocking motion to the shaft 4, and the arm 7 on the latter imparts a rocking motion to the carrier 3, which carries the arm 2, having the thread-guide at the upper end in the form of an opening or hole constituting the thread-bearing.

The thread-guide arm 2, Fig. 2, is pivoted 55 to the carrier 3, so as to swing to and from the cop-shaft 1, whereby, as the size of the cop increases, the arm 2 is thrown back, and this movement of the arm is the means of adjusting the pin 5 in the slot *x*, so as to gradually 60 reduce the lateral reciprocating motion imparted to the guide from the shaft 4, thereby building up a cop gradually contracting in width from the hub toward the outer edge.

It will be seen that the thread-bearing of 65 each guide is so arranged that the thread is delivered directly from the guide to the face of cop—that is, there is practically no play between the point of delivery of the thread from the guide and the point where the thread reaches the cop. This is a matter of the utmost importance, because it has proved in practice that if there is an opportunity for the thread to play it will not deliver properly onto the cop, and the latter will begin to build 70 75 irregularly and the irregularity will increase until the character of the cop is entirely destroyed. Further, if there is any such play and the guide is reciprocated with extreme rapidity, as it is in some instances, then the 80 thread will be thrown out of place.

Different means may be employed for shifting the position of the stud 5 in the slot *x*, according to the position of the arm 2. Thus the stud 5 may be carried by a sliding block 6, 85 mounted to slide in a slot in the carrier 3, and pressed upward by a plate-spring 16, and the block 6 has a forwardly-inclined edge *y* against which bears a transverse edge or shoulder *z* of the guide-arm 2. When, therefore, the said 90 guide-arm is thrown back in the direction of its arrow, the shoulder *z*, bearing on the inclined edge *y*, causes the block 6 to be thrown downward to a greater or less extent, carrying with

it the stud 5, thereby reducing the distance between the stud and the axis of the shaft 4, and consequently reducing the throw imparted to the carrier 3 by the movement of the arm 7 on said shaft.

5 The carrier 3, Fig. 4, and the thread-guide arm 2 are slotted for the passage of the shaft 4, as shown.

10 The expansion holder *a* for the cop-tube X may be made in different ways. I prefer, however, to make it in the form of a longitudinally-split sleeve *u*, Fig. 5, upon a tapering end of the shaft 1 and with a circular head 19, having an annular groove *b*, and into the 15 said groove *b* enters a lug 20 on a lever 21, which may be swung outward to carry the split sleeve forward and permit the members thereof to contract and receive the cop-tube, and then may be carried back to the position 20 shown in Fig. 5, expanding the sleeve in the cop-tube and holding the latter firmly in place.

25 In order to wind the cop in the manner described in my Letters Patent before referred to, it is necessary to impart such a relative difference of movement to the cop-winding shaft and to the thread-guide that the thread when brought to either end of the cop will be laid either just back of or just in advance of the thread previously laid at that point—that 30 is, there is not only a complete revolution of the cop to each reciprocation of the thread-guide, but also an increment of movement sufficient to cause the new thread to be laid in advance of the position it would otherwise 35 occupy, or instead of a complete revolution there is at the termination of each movement of the guide a partial revolution of the cop sufficient to permit the new thread to be laid back of that previously laid. I secure this 40 difference in the relative movements by connecting together the cam 13, which drives the thread-guide and the shaft 1, which drives or carries the holder for the cop, by means of gears so constructed that one or other of said 45 gears may have either a slight increase or a slight decrease in its movement in respect to the others. Thus the gear-wheel 23 upon the shaft 1 is geared through an intermediate gear-wheel 24 with a gear-wheel 25 carried by 50 but turning upon the shaft 29, to which is secured the cam 13. The shaft 29 carries a yoke 22 in which turns a shaft 24 carrying a pinion 30 that meshes with the teeth of a gear 27 upon an annular flange 26 of the gear-wheel 25.

55 A friction-wheel 31 upon the shaft 24 is in frictional contact at its periphery with a stationary plate 32, and when the friction-wheel 31 is in a position coincident with the axis *t* of the shaft 29, the revolution of the shaft 29 will 60 not impart any corresponding revolution to the gear 25 or to the connected frame. When, however, the friction-wheel 31 is shifted to one side of the axis *t*, then it will travel upon the plate 32 as the shaft 29 revolves, and consequently the pinion 30 will travel upon the gear 27 and impart either more or less motion 65 to the gear 25 than the shaft 29 has, so that

the gear 25 either revolves to a slightly-greater extent than the shaft 29 or to a slightly-less extent than said shaft, giving the movement before referred to. By making the wheel 31 adjustable upon the shaft 24, the degree of this movement may be varied to any desired extent so as to secure the requisite adjustment with the greatest nicety.

75 I do not here claim the construction of device for securing the requisite variation in the movements of the cop-holder and thread-guide, as the same constitutes the subject of a separate patent, No. 506,959.

80 It will be understood that it is exceedingly desirable in winding small cops or bobbins for sewing-machines to avoid the use of a multiplicity of winding apparatus, while at the same time it is necessary to impart the requisite movements and variations of movements 85 before described to each spindle carrying a cop-tube and its coacting thread-guide. In order to secure this desirable result, I combine with a series of cop-winding shafts 1 and 90 with a series of thread-guides a single regulating device of the character described, or of any other suitable character that will impart the requisite variations of movement. One means of effecting this is illustrated in Fig. 1, 95 where it will be seen that the shafts 4 and 15 are prolonged so that the shaft 4 carries a series of arms 7 and the shaft 15 a series of thread-guide carriers 3, and that there is a series of shafts 1.

100 The series of shafts 1 are connected so as to rotate together by means of intermediate gears, as shown and indicated, while the single cam 13 drives both of the shafts 15 and 4 and imparts the requisite movement to the 105 various thread-guides in their proper relation to the rotation of the cop-shafts.

110 It has been found that if the tension upon the thread is maintained uniform throughout the winding of a cop—that is, when the thread is of elastic material, especially such thread as silk—the outer layers or windings compress the inner layers or windings so that the sides of the cop are forced outward. I avoid this by gradually reducing the tension as the 115 size of the cop increases. One means of effecting this is by applying a friction-brake to the tension device and gradually reducing the force of this brake. Thus, I carry the thread, 120 Fig. 2, around a friction-brake wheel 33, having a peripheral groove to receive the thread, and against the shaft or hub on the shaft 45 of said friction-wheel bears a brake 35 at the end of a lever 34. A movable weight shown in the 125 form of a heavy roller 37 rests upon the lever 34, and is caused to travel nearer the fulcrum of the latter in proportion as the size of the cop increases. Thus a pin 44 on a lever 42 pivoted at the lower end bears against the guide-arm 2, so as to be swung back as the said guide-arm 130 is swung back, and a pin 41 upon the lever 42 bears against the edge of a pivoted lever 39, forked at the upper end and having a slot in each fork to receive the shaft 47 of the

weight 37. As the guide-arm 2 swings back it carries with it the levers 42 and 39 and the weight 37, so that as the size of the cop increases and bears back the guide-arm 2 the weight 37 is carried nearer to the fulcrum of the lever 34, and the effect of the friction-brake 35 decreases, relieving the thread of tension.

It is desirable to arrest the movement of the machine the instant that a cop is filled. I therefore provide means whereby this may be automatically done. Thus each shaft 1, Fig. 4, instead of being rigidly connected with its gear 50, is connected through the medium of a clutch consisting, as shown, of a tapering hub 51, which is upon the gear 50 and with the latter turns loosely upon the shaft 1, and a movable clutch-piece 52 splined to the shaft 1, having a socket to receive the hub 51 and tapering to correspond therewith and with an annular shoulder v , the piece 52 being pressed toward the hub 51 by a spring 54, and when the two parts are in contact the shaft 1 turns with the gear 50; but when the part 52 is thrown out the shaft will remain stationary while the gear 50 turns. A lever B having a handle d and a cam-arm 55 may be thrown in one direction to the left, Fig. 5, to bring said arm against the shoulder v and throw out the piece 52 to the left, a spring 56, Figs. 4 and 5, tending to throw the arm 55 in this direction. The arm 55 has a shoulder or lug 57, Figs. 5 to 10, which engages with a suitable detent, as a spring 58, and over the latter extends an eccentric or cam 59 upon a shaft carrying an arm 60, Figs. 4 and 7, that terminates in the stop t .

The stop t is in such a position that when the thread-guide arm 2 is carried back to a sufficient extent by the completion of the bobbin a contact-piece s upon the said arm will, as the arm swings inward, strike the stop t , rock the arm 60 and its cam 59 in the direction of the arrow, Figs. 4 and 7, and bring the said cam to bear upon and depress the spring 58 to carry it from the shoulder 57, when the spring 56 will force down the arm 55 of the lever B, and thereby force back the piece 52 of the coupling and uncouple the shaft 1 from the gear 50.

In order to reset the parts, I make use of the cam w^2 on the end of the lever d , which passes through a slot w' in the arm 55, the cam w^2 making contact with the spring or detent 58 when the handle is swung to one side, depressing the spring, and the handle then takes a bearing on the arm 55 and swings the latter. The pins 9 12 are upon a slide adjustable on the arm 10, so as to vary the extent of movement imparted by the cam 13 by carrying the slide nearer to or farther from the axis of the arm 10.

It will be evident that while I have shown a series of vibrating reciprocating carriers for the thread-guides, said carriers may each slide in straight lines, as in the machine constituting the subject of my Letters Patent No.

506,959. Although I have shown in this application some devices for securing an increment of movement, (shown in my aforesaid Patent No. 506,959,) I do not herein claim the same except in the particular combinations set forth. Neither do I here claim a brake combined with a tension device with means for varying the power of the brake, as in my Patent No. 509,413.

Without limiting myself to the precise construction and arrangement of parts set forth, I claim as my invention—

1. The combination of a cop-shaft, an expansion-spindle for the cop-tube adapted to be carried by the shaft, and means including an operating-handle 21, for expanding the spindle, when the tube is fully on the spindle, substantially as and for the purpose set forth. 85

2. The combination of a cop-shaft having a conical termination 1, a split sleeve adapted to said termination, and to receive a cop-tube, and means including an operating-handle 21 for sliding the sleeve over the said termination to expand and contract the same, substantially as set forth. 90

3. The combination of the series of cop-shafts, spindles, and reciprocating guides and guide-carriers, each guide connected to be independently movable to and from the cop-shaft, with its eye at the point where the guide bears on the cop, and supported to maintain contact with and deliver the thread directly to the cop, means for varying the extent of reciprocation of the reciprocating carriers, and connections between the said means and the guides whereby the movement of the latter from the spindles is made the means of reducing the reciprocating movements of the carriers, substantially as set forth. 100

4. The combination of the cop-shaft, the reciprocating carrier, guide connected to said carrier and movable to and from the cop-shaft, at right angles thereto to maintain contact with the cop, a vibrating arm for imparting motion to the carrier, a pin extending from the carrier and having lateral contact with the guide and means as a block having an inclined shoulder on the block and bearing on the guide and a spring for moving the said pin toward and from the axis of the arm, substantially as described. 110

5. The combination of the cop-shaft, the vibrating carrier 3, the guide-arm movable to and from the cop-shaft, and connected to said carrier, a pin extending from the carrier and entering a slot in the reciprocating guide-arm, and a block vertically movable on the carrier connected with said pin and having an inclined edge adapted to a transverse bearing of the guide-arm, substantially as set forth. 125

6. The combination of the revolving cop-shaft, a rock-shaft 15, a carrier 3, connected to the shaft 15, a guide-arm 2, pivoted to the carrier 3, a rock-shaft carrying an arm 7, a pin projecting from the carrier and having bearings upon the arm 7 and means connected to be operated from the arm 2 for automatically ad-

justing said pin as the guide-arm moves outward from the cop-shaft, substantially as set forth.

7. The combination with the cop-shaft, carrier, guide-arm 2 supported by the carrier, shaft 4, having an arm 7 with bearings for a pin extending from the carrier, a cam-wheel 13 and an arm 8 extending from the rock-shaft 4, and a bearing between the cam-wheel and 10 the said arm 8 adjustable toward and from the rock-shaft, substantially as set forth.

8. The combination of a series of cop-shafts connected to turn together, a series of separate reciprocating thread-guides, each arranged to 15 maintain contact with the cop and deliver the thread without play thereto, and means for positively reciprocating all of said guides and gearing adjustable to insure an increment of motion between the guide-reciprocating 20 means and the cop-shafts, substantially as set forth.

9. The combination of a series of cop-shafts, a thread-guide to each shaft, a series of carriers for the thread-guides a single rock-shaft 25 reciprocating said guides, the guides pivoted to the carriers to swing independently to and from the cop-shafts to maintain contact with the cops, thread-bearings arranged on the guides to deliver the thread directly to the face 30 of each cop, and means for rocking the rock-shaft, substantially as set forth.

10. The combination of the series of cop-shafts, a shaft carrying a series of carriers, each carrier with a guide for the thread connected to maintain constant contact with the cop, another shaft having a series of arms, each carrier with a pin having its bearings upon one of the arms of the latter shaft, substantially as set forth.

40 11. The combination of a series of cop shafts and holders connected to revolve together, a series of separate thread-guides and means

for reciprocating them each adjacent to one of the cop-holders and gearing between the cop-operating and guide-operating devices adjustable to vary their relative movements, and means for throwing the cop-shafts independently into and out of operation, substantially as and for the purpose set forth. 45

12. The combination of the revolving cop-shaft, the reciprocating thread-guide, movable to and from the shaft, a friction device having an arm 34, and movable weight thereon, and levers 39, 42, between the weight and the thread-guide, substantially as and for the 50 purpose set forth.

13. The combination with the driving devices and stop motion of a thread-winding machine, and with the reciprocating thread-guide thereof, of a detent as a spring 58, for holding 55 the stop-motion out of action, a stop *t*, and means connected therewith for moving said detent, and a projection *s* upon the guide arranged to make contact with said stop when the guide is in its terminal position, substantially as set forth.

14. The combination of a series of cop shafts and holders connected to turn together, means for throwing each shaft out of operation, a series of thread-guides and means for reciprocating the same, each guide supported to move away from the axis of the cop-shaft as the cop increases in size, and gears arranged and constructed to vary the relative movements of the cop shafts and guides, substantially as and 70 for the purpose set forth.

In testimony whereof I have signed my name to this specification in the presence of two subscribing witnesses.
